UNITED STATES PATENT OFFICE.

JOHN J. MACAULEY, OF GRAND RAPIDS, MICHIGAN.

OIL-BURNER.

1,364,637.

Specification of Letters Patent.

Patented Jan. 4, 1921.

Application filed June 21, 1920. Serial No. 390,362.

To all whom it may concern:

Be it known that I, JOHN J. MACAULEY, a citizen of the United States of America, residing at Grand Rapids, in the county of 5 Kent and State of Michigan, have invented certain new and useful Improvements in Oil-Burners; and I do hereby declare the following to be a full, clear, and exact description of the invention, such as will enable others skilled in the art to which it 10 pertains to make and use the same.

This invention relates to an oil burner, being particularly concerned with a burner for the heavier hydrocarbon oils in which the 15 oils may be heated and generated into a gas and properly mixed with air after which the same may be burned, the heat of combustion serving to generate the oil thereafter burned into a gas for further combustion. It 20 is a primary object and purpose of the present invention to make a burner of this character of few parts and one very simply constructed yet one particularly effective in service. Many other objects and purposes 25 will appear as understanding of the invention is had from the following description taken in connection with the accompanying drawing, in which,

Figure 1 as a vertical section taken centrally through the burner, and

Fig. 2 is a horizontal section taken on the line 2—2, of Fig. 1 and looking in the direction indicated by the arrows.

Like reference characters refer to like 35 parts in the two figures of the drawing.

In the construction of the burner, a hollow vertical sleeve 1 is used in which at its upper end a number of openings 2 are made, there being four shown in the drawing, 40 though this particular number of openings is not absolutely essential. The sleeve is made from any suitable metal and at its lower end is turned outwardly and upwardly making an annular depression above 45 the outturned portion 3, and terminating in a horizontally positioned flange 4 which is adapted to rest on the plate 5 in which an opening is cut into which the lower portion of the burner may be inserted as shown. A 50 downwardly extending annular lip 6 is made integral with the sleeve being slightly larger in diameter as shown and into the same an air pipe may be inserted as indicated in dotted lines for carrying air under pressure to 55 the sleeve. The forced air draft is not neces-

sary, however, and the pipe indicated in dotted lines need not be used if not desired.

A head including a horizontal plate 7 and a downwardly extending sleeve 8 is placed over sleeve 1 being located by a bead 7^a 60 which fits within the upper end of said sleeve 1. The sleeve 8 extends to a point a short distance above the outwardly extending part 3 and is slightly enlarged adjacent its lower end as indicated at 8^a. Near where 65 it joins with the plate 7, sleeve 8 is provided with a plurality of openings 9 made in spaced apart relation through the sleeve and at a lower point, substantially at the point of enlargement of the sleeve, with a 70 plurality of spaced apart openings 10. A conical generator sleeve 11 is placed around the sleeve 8 joining therewith at its lower end and extending upwardly and outwardly to the outer edges of the plate 7 as shown. 75 On its inner side member 11 is formed with a continuous rib 12 thereby forming an annular recess back of the rib and between it and said member.

An oil supply pipe 13 extends vertically 80 through the sleeve 1 and connects with a cross pipe 14 which passes through the openings 2 and through sleeve 8, the ends thereof coming above the recess back of the rib 12. Oil is carried through a pipe 15 to the 85 pipe 13 and is controlled in passage by a valve 16 opened and closed by operating the wheel 16^a.

The air passes upwardly through sleeve 1 and out through the openings 2 to the space 90 between sleeves 1 and 8 and thence downwardly. Gas from the oil passes out through the openings 10 and mixes with the air and the mixture is burned at the mouth at 17 of the mixing chamber made by the 95 enlargement of the sleeve 8 at its lower end. This creates a suction and the enlargement of the sleeve at 8^a is in effect a Venturi construction aiding in creating suction and drawing the gases through openings 10 into 100 the mixing chamber. The flame from burning is directed upwardly along the outer sides of the member 11 heating the same and causing oil coming in contact therewith to be heated to a high degree of temperature 105 and generated into a gas. At the start, when the burner is to be lighted oil may be placed in the depression above the portion 3 of the burner and burned to initially heat the generating member 11. Any oil coming 110

from the ends of pipe 14 is delivered into the annular recess back of rib 12 and flows evenly over the top thereof on to the generator member 11 whereby a uniform distribution of oil and complete generation thereof into gas is had. If at any time it is desired to clean out the interior of the generating chamber, the same may be done by removing the plugs 18 threaded through the 10 plate 7 as shown.

This burner is of very simple construction and made at a very low cost of manufacture, requiring little or no machining and made chiefly from simple castings. In 15 practice it has proven its complete success. The appended claims define the invention and I consider myself entitled to all forms of construction falling within their scope.

I claim:

20 1. In combination, a central vertical sleeve having openings therein at its upper end, said sleeve being extended outwardly and upwardly at an angle at its lower end, a burner head comprising an upper horizontal 25 plate and a depending sleeve placed over the first sleeve, said second sleeve being spaced from the first sleeve and the plate resting on the upper end of the first sleeve, said second sleeve having a plurality of upper and lower openings therethrough, a conical shaped generator member being disposed around the second sleeve and extending upwardly from the lower end of the second sleeve to the outer edges of the plate, said generator 30 member being formed with an annular rib on its inner side, an oil carrying pipe passing upwardly through the first sleeve, and a second pipe connected to the upper end of the oil pipe, the ends thereof coming above 35 the rib on the generator member, substantially as described.

2. In combination a burner comprising a central air conducting sleeve with openings therethrough at its upper end, a second 45 sleeve around the first sleeve having a plurality of upper and lower openings therethrough, a conical shaped generator member around the second sleeve and extending upwardly and outwardly from the lower end 50 of the second sleeve, a plate integral with the second sleeve covering the air conducting sleeve, the mixing chamber between the sleeves and the generator chamber between the second sleeve and the generator member, means formed integral with the air conducting sleeve below the lower end of the second sleeve for directing the flame from the burner upwardly against the generator member, and means to carry fuel in liquid 55 form to the generator member and distribute the same over the generator member on its inner side.

3. A burner comprising a central vertical sleeve having openings therethrough at its upper end, a plate resting on the upper end 60

of the sleeve and extending a distance beyond the sleeve, a second sleeve integral with the plate depending therefrom and spaced from the first sleeve, said first sleeve at its lower end being continued outwardly and upwardly to form a recessed portion a short distance below the lower end of the second sleeve, and said second sleeve having a plurality of upper and lower openings therethrough, a conical shaped generator member 75 around the second sleeve and disposed between the lower end thereof and the outer edges of the plate, means to carry liquid fuel to the inner sides of the generator member, and means for evenly distributing the same 80 over said inner sides of the generator member, substantially as described.

4. In a burner, inner and outer sleeves spaced a short distance apart, said inner sleeve having openings therethrough at its upper end and turned outwardly and upwardly at its lower end, said outer sleeve having a plurality of upper and lower openings therethrough and terminating at its lower end short of the outturned portion of 90 the inner sleeve, a conical shaped generator member around the outer sleeve and extending upwardly and outwardly from the lower end thereof, an upwardly and inwardly extending rib located horizontally on the inner 95 side of the generator member, a plate integral with the outer sleeve covering the upper end of the burner, and means to carry liquid fuel to the generator member above the rib on the inner side thereof, substantially as described.

5. In a burner, a generator member having upwardly and outwardly inclined sides, a sleeve around which said generator member is placed, said sleeve having openings 105 therethrough, a cover plate covering the space between the sleeve and generator member, means to carry air to mix with gases passing through the openings in the sleeve, said mixed air and gases being adapted to 110 burn at the lower end of the sleeve, means to direct the products of combustion upwardly against the outer sides of the generator member, means to carry liquid fuel to the inner sides of the generator member, 115 and means to distribute said fuel evenly over the inner sides of said generator member, substantially as described.

6. A burner comprising an inner vertical sleeve having openings therethrough at its upper end, said sleeve at its lower end being turned outwardly and upwardly, a plate resting on the upper end of said sleeve, an outer sleeve depending from the plate and spaced from the inner sleeve, said outer 120 sleeve being shorter than the inner sleeve and enlarged at its lower portion and provided with a plurality of openings therethrough immediately below the plate and a second plurality of openings in its lower 125 130

portion substantially at the beginning of the
enlargement thereof, a generator member
around the outer sleeve and extending up-
wardly and outwardly from the lower end
5 of the outer sleeve to the edges of the plate.
said generator member having an upwardly
and inwardly extending horizontal annular
rib on its inner side, a fuel carrying pipe pass-
ing upwardly through the inner sleeve, and

a horizontal pipe connected to the upper 10
end of the fuel carrying pipe and passing
through the sleeves, the ends of the horizon-
tal pipe being open and terminating directly
above the annular recess back of said rib on
the generator member, substantially as de- 15
scribed.

In testimony whereof I affix my signature.
JOHN J. MACAULEY.
